UNITED STATES PATENT OFFICE.

HENRY J. SCHMICK, OF HAMBURG, PENNSYLVANIA.

DESIGN FOR A RADIO-HELICAL CAM.

SPECIFICATION forming part of Design No. 34,659, dated June 11, 1901.

Application filed May 7, 1901. Serial No. 59,184. Term of patent 14 years.

To all whom it may concern:

Be it known that I, HENRY J. SCHMICK, a citizen of the United States, residing at Hamburg, in the county of Berks and State of Pennsylvania, have invented and produced a new and original Design for Radio-Helical Cams, of which the following is a specification, reference being had to the accompanying drawings, showing the same.

10 Figure 1 represents a side elevation showing my design; Fig. 2, an end view taken on the line 2 2, Fig. 1, and looking in the direction of the arrow; and Fig. 3, a top plan view of the same, these views being deemed necessary to illustrate my design.

15 The leading feature of my design consists in a cylinder A, on whose wall and on each side of the longitudinal center thereof are formed a plurality of working surfaces or 20 dwells B in a helical path, as indicated by

the dotted line C in Fig. 1, and said dwells terminate in a neck D, which is connected or joined at its outer end to the crank E, to which the shaft F is connected, and to the head G of the cylinder or cam the opposite shaft H is connected in the axial plane of the cam.

25 The cam viewed from its end, as shown in Fig. 2, represents an approximate unguula.

Having described my invention, what I 30 claim as new, and desire to secure by Letters Patent, is—

The design for a radio-helical cam, substantially as herein shown and described.

In testimony whereof I affix my signature 35 in presence of two witnesses.

HENRY J. SCHMICK.
